UNITED STATES PATENT OFFICE

HOWARD BROWN, OF LONGMEADOW, MASSACHUSETTS, ASSIGNOR TO SOUTHWORTH COMPANY, OF MITTINEAGUE, MASSACHUSETTS, A CORPORATION OF MASSACHUSETTS

METHOD OF PREPARING WATERMARKING PLATES

Application filed May 15, 1930. Serial No. 452,796.

This invention relates to a method of preparing water-marking plates for use in a Fourdrinier or other paper-making machine.

In my prior Patent No. 1,261,902, issued April 9, 1918, I have described the production of water-marks or impressions in paper by pressing an engraved or electrotype plate against the paper web while the material is in a partially dried and still plastic condition. By the application of the plate in this manner and at this point in the formation of the paper, very fine and intricate designs may be produced on the paper. It is necessary, however, that the impression surface of the water-marking plate be extremely accurate and uniform, as any slight variation in thickness or adjustment of the plate is clearly seen in the paper.

In my prior Patent No. 1,362,598, issued December 21, 1920, I have described a machine in which water-marking plates may be proved and justified.

My present invention relates to an improved method of procedure by which such plates may be more effectively prepared for use.

It is the general object of my invention to improve the method heretofore practiced in preparing water-marking plates for use, to the intent that more perfect impressions may be attained.

My invention relates particularly to the improved method hereinafter described and more particularly pointed out in the appended claims.

A machine by the aid of which the process may be carried out is shown in the drawings, in which

Fig. 1 is a partial perspective view of the machine; and

Figs. 2, 3 and 4 are views illustrating the carrying out of my improved process.

Referring to Fig. 1, I have shown a base 10 mounted upon rollers 11 and adapted to be guided by rails 12 toward and from a paper-making machine. A bed roll 14 is mounted in bearings 15 supported in end frame members 16. The roll 14 is preferably formed of metal and in any event is provided with a smooth hard surface.

A marking roll 20 is mounted above the roll 14 and is provided with bearings 21 slideable in the guideways of the end frame 16. The bearings 21 are pressed downward by weights 22 acting through levers 23 and plungers 24.

Any simple means may be used for limiting the approach of the marking roll 20 to the bed roll 14. For instance, a wedge 26 may be interposed between the bearings 15 and 21 and may be adjusted crosswise of the frame 16 by an adjusting screw having a hand wheel 28 by which it may be turned.

The rolls 14 and 20 are provided with connecting gears 30, so that they may be rotated in unison. The bed roll 14 is also provided with a hand wheel 31 and with a pulley 32, connected by a belt 33 to a pulley 34 on the armature shaft of a motor M.

The marking roll 20 and bearings 21 form part of the usual equipment of the watermarking attachment of a paper-making machine and are removed bodily from the paper-making machine when stereotype plates are to be applied thereto or justified for use. The bed roll 14 and bearings 15 may also form a part of the marking attachment of a paper-making machine but more commonly the roll 14 remains as a permanent part of the proving machine.

My improved method of perfecting and justifying the water-marking plates is preferably carried out as follows:—

I first attach the plates 40 to the marking roll 20 by the usual screws or in any other convenient manner. I then run a strip or web of paper W (Fig. 2) between the rolls 14 and 20 and adjust the bearings of the marking roll so that the plates can engage the paper.

I then turn the rolls back and forth by the hand wheel 31 to test the impression, and I carry out the usual steps of building up the low places on the plates by inserting thin paper cut-outs behind the plates. In this way the plates are brought into approximately correct positions.

Such water-marking plates, and particularly stereotype plates, are subject to more or less inaccuracies and rough edges or pro-

jections, and I now proceed to "break-in" the new plates by removing the paper W and rotating the rolls for a considerable period by means of the motor M, with the plates 40 in direct engagement with the smooth hard surface of the bed roll 14. In this way the surface of the electrotype plates is smoothed out by rolling engagement with the surface of the bed roll, and the uniformity and accuracy of the impression is much improved.

10 During this operation, the wedges may be slightly withdrawn to permit a more firm contact between the rolls. After rotating the rolls in this way for a sufficient period, the web of paper is again introduced and further proving and justification is carried out, after which further "breaking-in" follows, if found desirable.

20 By thus alternating the "justifying" and the "breaking-in" steps, the plates are quickly worked down to a smooth uniform working surface, so positioned that a substantially perfect impression may be obtained. This result is much more quickly and easily produced than by the methods heretofore practiced.

30 My improved method is not only applicable to justifying and breaking-in a plurality of new stereotype plates, but is also useful when one or two worn or damaged plates of a series are replaced by new plates. It has been found heretofore that the new plates would produce a sharper impression and a different appearance from plates which had been used for a longer or shorter period. By placing the marking roll in the proving machine above described and breaking-in the new plates by rotation against the bed roll, the impressions of the old and new plates may be quickly equalized, so that the insertion of new plates will not be evident.

40 Having thus described my invention and the advantages thereof, I do not wish to be limited to the details herein disclosed, otherwise than as set forth in the claims, but what I claim is:—

1. The method of preparing water-marking plates for use in a paper-making machine which consists in mounting the water-marking plates upon a marking roll, proving and justifying the surface of the plates with respect to an associated bed roll and with respect to a web of plastic paper material passed between said plates and said bed roll, and in thereafter rotating said rolls for a substantial period with said water-marking plates directly engaging the smooth hard surface of the bed roll, whereby all parts of the impression surfaces of said plates are brought into effective marking alignment.

2. The method of preparing water-marking plates for use in a paper-making machine which consists in mounting the water-marking plates upon a marking roll, proving and justifying the surface of the plates with re-

spect to an associated bed roll and with respect to a web of plastic paper material passed between said plates and said bed roll, in thereafter rotating said rolls for a substantial period with said water-marking plates directly engaging the smooth hard surface of the bed roll, and in repeating said justifying and said rotating operations until satisfactory and uniform impression surfaces on said plates are produced.

3. The method of preparing water-marking plates for use in a paper-making machine which consists in mounting the water-marking plates upon a marking roll, mounting said marking roll adjacent a bed roll having a smooth hard surface, rotating said rolls with said plates in direct contact with said bed roll, and in applying substantial pressure to said rolls while said rolls are thus rotated.

4. The method of preparing water-marking plates as set forth in claim 3, in which the rolls are rotated by power for a substantial period of time.

5. In testimony whereof I have hereunto affixed my signature.

HOWARD BROWN.
